F. T. AHERN.
TOY.
APPLICATION FILED APR. 7, 1917.

Patented May 14, 1918.

Inventor
Frank T. Ahern
By his Attorney
Wm. H. Black

UNITED STATES PATENT OFFICE.

FRANK T. AHERN, OF NEW YORK, N. Y., ASSIGNOR TO FERDINAND STRAUSS, OF YONKERS, NEW YORK.

TOY.

1,265,718.

Specification of Letters Patent.

Patented May 14, 1918.

Application filed April 7, 1917. Serial No. 160,376.

To all whom it may concern:

Be it known that I, FRANK T. AHERN, a citizen of the United States of America, residing at New York city, county and State 5 of New York, have invented certain new and useful Improvements in Toys, of which the following is a full, clear, and exact description.

This invention relates to improvements in 10 toys the object being to provide a toy in the form of a miniature gun or cannon which is mounted on wheels and arranged to be pushed or pulled by a child.

In combination with the representation 15 of a gun or cannon means are provided whereby the report of the rapid firing of the gun can be imitated while the toy is being propelled. The gun or cannon is provided with a plunger by which means small articles such as marbles, balls of paper, etc., can 20 be fired or expelled therefrom at the will of the child.

I will now proceed to describe my invention in detail, the novel features of which 25 I will point out in the appended claim reference being had to the accompanying drawing forming part hereof, wherein—

Figure 1 is a longitudinal sectional view 30 of my improved toy, certain parts being shown in elevation, and

Fig. 2 is a plan view thereof.

As herein embodied, my invention consists of a carriage or frame-members 3 and 4 through which a rotatable axle 5 passes 35 said axle carrying wheels 6 and 7. To the carriage or frame-members 3 and 4, I pivotally secure at 8 the barrel 9 which represents the barrel of a cannon. The barrel 9 is provided with a bore 10 within which I 40 locate a longitudinally movable plunger 11, which is surrounded by a spring 12 adapted to be compressed when the plunger 11 is pulled toward the left in Fig. 1. When the plunger is released, after having been pulled 45 toward the left, thereby compressing the spring 12, the reaction or expanding of the spring will force the plunger to the right, thereby expelling any article which has

been placed in the barrel through the muzzle 13.

Upon the axle 5, I place a disk 14 having outwardly projecting teeth 15, to provide recesses 16, against which a yieldable tongue 17 bears. One end of the tongue 17 is rigidly secured to the carriage members as at 50 18; the other end of said tongue is free to brush against the teeth 15 and to be forced or snapped into the recesses by the spring action of the tongue 17. The tongue is 55 preferably made of wood, as is the disk 15, but other material could be used.

When the device is pushed or pulled, the 60 wheels 6, and axle 5, will rotate as will also the toothed disk 15. While the disk is revolving, the tongue 17 will be rapidly raised 65 and lowered, in other words, the teeth 16 will raise the tongue which will snap into the recesses, and against the tooth 16 thereunder, thereby creating a report not unlike the report of a rapid firing gun. In order 70 that a handle can be attached to the toy, I provide an opening 19 to receive it.

What I claim is:

In a device of the kind described, in combination, a carriage consisting of a flat base 75 portion, a pair of laterally spaced triangular frame members integrally formed upon said flat base portion of said carriage, an axle passing through the lower front ends of said frame members, a cannon barrel 80 mounted between the upper front ends of said frame members, a star wheel fixed upon said axle between said frame members, a pair of wheels secured to the free ends of said axle for rotating the latter, and a yieldable elongated tongue, having one end fixedly secured within said flat base portion, 85 said tongue extending longitudinally between said frame members and engaging the teeth of said star wheel. 90

Signed at New York city, N. Y., this 6th day of April, 1917.

FRANK T. AHERN.
